UNITED STATES PATENT OFFICE

MAX ALBERT KUNZ, OF MANNHEIM, AND KARL KOEBERLE, OF LUDWIGSHAFEN-ON-THE-RHINE, GERMANY, ASSIGNEES TO GENERAL ANILINE WORKS, INC., OF NEW YORK, N. Y., A CORPORATION OF DELAWARE

VAT DYESTUFFS

No Drawing. Application filed December 14, 1929, Serial No. 414,244, and in Germany December 15, 1928.

The present invention relates to the manufacture and production of vat dyestuffs.

We have found that vat dyestuffs having very varied shades and properties, and which in many cases may be employed as intermediates for the manufacture of other vat dyestuffs are obtained by treating with condensing agents having a reducing action 1,1'-dianthraquinonyls of the following general formula:

in which X and Y may be hydrogen or halogen, the oxygen atoms in the 9 and 9' positions and the hydrogen atoms in the 8 and 8' positions may be replaced by linkages connecting the said positions with each other and in which the anthraquinonyl radicles may be substituted. By the term condensing agents having a reducing action we intend to comprise the usual acid or alkaline condensing agents to which reducing agents have been added, as well as compounds as by themselves act as condensing and reducing agents simultaneously. As acid condensing agents there may be employed sulphuric acid or derivatives thereof, such as for example oleum or chlorosuphonic acid to which reducing agents have been added as which may be mentioned metals, for instance copper, aluminium, zinc and the like, or reducing compounds thereof, such as cuprous oxide, cuprous halides, or metal sulphides. Alkaline agents which may be made use of are for example solutions of the hydroxides of alkali metals or alkaline earth metals or alkaline compounds of the said metals, such as carbonates, acetates and the like, to which re-

ducing agents, such as for example alkali metal hydrosulphite, hydrazine, hydroxylamine, alkali metal or alkaline earth metal sulphides have been added. Condensing agents which at the same time have a reducing action are, for example, pyridines, hydrazinehydrate, phenylhydrazine, aniline, dimethylaniline, ethanolamine, cyclohexylamine and the like.

By the action of the said condensing agents having a reducing action different products are obtained, namely for example from omega-omega'-tetrabromo-2,2'-dimethyl-1,1'-dianthraquinonyl 2,2'-ethylene-1,1'-dianthraquinonyl, allo-ms-naphthodianthrone and ms-anthradianthrone. The reactions proceed somewhat as shown in the following diagram:

Generally speaking, the said products are produced simultaneously though in different

amounts according to the working conditions which however may be varied so as to obtain one of the aforesaid products as the main or even as the sole product. For example 2,2'-ethylene-1,1'-dianthraquinonyl is obtained as the main product in the reduction of omega-omega'-tetrabromo-2,2'-dimethyl-1,1'-dianthraquinonyl with weak alkaline reducing agents as for example sodium hydrosulphite in alkaline solution, while allo-ms-naphthodianthrone is formed in a yield of more than 90 per cent of the theoretical yield by reduction in acid media at low temperatures, i. e. below about 50° C. Allo-ms-naphthodianthrone is also obtained as the main or even exclusive product when treating initial materials in which the 9,9'-positions are linked together, i. e. from omega-omega'-tetrahalogen-2,2'-dimethyl-ms-benzdianthrone by means of alkaline condensing agents having a reducing action at any temperature. Anthradianthrone is obtained as main product by first treating omega-omega'-tetrahalogen-2,2'-dimethyl-1,1'-dianthraquinonyl in acid media at low temperatures and then raising the temperature, or from the said initial material in which the 9,9'-positions and the 8-8'-positions are linked together in alkaline media.

The products may further be subjected to halogenation according to known methods, for example in organic solvents, water, sulphuric acid or derivatives thereof or in the absence of any solvent.

The crude products may be purified or separated from the other compounds simultaneously formed, if desired, by the usual methods as for example by crystallization from organic solvents of high boiling point, or by way of their oxonium salts or by treatment with organic solvents or alkalies or with oxidizing agents, for example by treating the aqueous pastes with sodium hypochlorite.

The following examples will further illustrate the nature of this invention but the invention is not restricted to these examples. The parts are by weight.

50

Example 1

380 parts of omega-omega'-tetrabromo-2,2'-dimethyl-1,1'-dianthraquinonyl, obtainable by the action of bromine on 2,2'-dimethyl-1,1'-dianthraquinonyl, are triturated with 400 parts of pyridine, poured into 4000 parts of water and are heated to from 70° to 80° centigrade on the water bath after the addition of 500 parts of 40 per cent caustic soda solution and 150 parts of sodium hydrosulphite. A clear violet wine red solution is thus obtained. If necessary any impurities present are filtered off by suction and the dyestuff

free from halogen which has been formed is precipitated by blowing in air, and the precipitate is filtered off by suction and dried. It is a yellow orange powder which dissolves in concentrated sulphuric acid giving an olive green coloration and gives a violet wine red vat from which cotton is dyed yellow orange shades. By purification, for example by extraction with pyridine, pure 2,2'-ethylene-1,1'-dianthraquinonyl is obtained which crystallizes in yellow needles which melt at about 345° C. with decomposition, and which dissolves in concentrated sulphuric acid giving an olive brown coloration and dyes cotton orange yellow shades from an orange red vat.

Example 2

760 parts of omega-omega'-tetrabromo-2,2'-dimethyl-1,1'-dianthraquinonyl are suspended at about 0° C. in 7600 parts of concentrated sulphuric acid while stirring. 500 parts of copper power are added, the whole is kept at low temperature for several hours and then, if necessary, the whole is warmed for an hour at from 40° to 50° C. The green reaction liquid is freed from unchanged copper by filtration by suction, is poured into ice water and the precipitate is filtered off by suction and dried. The dyestuff thus obtained in a quantitative yield is identical with the allo-ms-naphthodianthrone obtained according to Example 1 of the application Ser. No. 199,420. It is an orange red powder, comparatively readily soluble in organic solvents of high boiling point and crystallizes therefrom in prismatic orange red needles which melt at about 350° C. The solution of the product in concentrated sulphuric acid is emerald green in color and shows a characteristic absorption line in the green region of the spectrum. It yields orange dyeings of very good fastness to washing and chlorine on vegetable fibres from a red violet vat. Instead of copper, other metals as for example aluminium bronze or zinc dust, or other reducing agents such as hydrazine hydrate and the like may be employed.

Example 3

100 parts of tetrabromo-2,2'-dimethyl-ms-benzdianthrone, containing the bromine in part in the nucleus, obtainable by brominating 2,2'-dimethyl-ms-benzdianthrone in nitrobenzene at between 160° and 170° C. are boiled, while stirring, in 2000 parts of pyridine until a sample furnishes a violet vat. The reaction mixture is then allowed to cool and the reaction product filtered off. The bromo-allo-ms-naphthodianthrone obtained in the form of copper-red needles dissolves in concentrated sulphuric acid to give a green

solution and dyes cotton strong brilliant red shades from a violet vat.

Example 4

5 88 parts of 4,4'-dichloro-omega-omega'-tetrabromo-2,2'-dimethyl-1,1'-dianthraquinonyl obtainable by brominating 4,4'-dichloro-2,2'-dimethyl-1,1'-dianthraquinonyl in nitrobenzene at between 160° and 180° C. are suspended at about 0° C. in 1000 parts of concentrated sulphuric acid. 80 parts of copper chips are then introduced into the reaction mixture which is stirred for several hours at between 5° and 10° C. and then allowed to warm to about 20° C. at which the reaction mixture is kept until it has a pure green coloration. The reaction mixture is then worked up as described in Example 2. The reaction product, 4,4'-dichloro-allo-ms-naphthodianthrone, is an orange powder furnishing on cotton orange dyeings from a violet vat.

Example 5

25 70 parts of omega-omega'-tetrachloro-2,2'-dimethyl-ms-naphthodianthrone obtainable by chlorinating 2,2'-dimethyl-ms-naphthodianthrone in boiling trichlorobenzene are introduced at between 120° and 130° C. into a melt of 200 parts of caustic potash and 200 parts of ethyl alcohol, while stirring, the reaction mixture being then heated to 180° C. and kept thereat until a sample furnishes a violet vat. The reaction mixture is then allowed to cool, taken up with water, the reaction product present as its leuco compound precipitated by blowing air through the reaction mixture and the reaction product filtered off. The product, probably ms-anthra-dianthrone, is a brown-yellow powder, dissolves in concentrated sulphuric acid to give a violet solution and dyes cotton very fast yellow shades.

What we claim is:—

45 1. A process for the manufacture of vat dyestuffs which comprises treating with a condensing agent having a reducing action 1,1'-dianthraquinonyls of the general formula:

in which X and Y may be hydrogen or halogen, the oxygen atoms in the 9 and 9' positions and the hydrogen atoms in the 8 and 8'

positions may be replaced by linkages connecting the said positions with each other and in which the anthraquinonyl radicles may be substituted.

2. A process for the manufacture of vat dyestuffs which comprises treating with an alkaline condensing agent having a reducing action 1,1'-dianthraquinonyls of the general formula:

in which X and Y may be hydrogen or halogen, the oxygen atoms in the 9 and 9' positions and the hydrogen atoms in the 8 and 8' positions may be replaced by linkages connecting the said positions with each other and in which the anthraquinonyl radicles may be substituted.

3. A process for the manufacture of vat dyestuffs which comprises treating with a weak alkaline condensing agent having a reducing action 1,1'-dianthraquinonyls of the general formula:

in which X and Y may be hydrogen or halogen, the oxygen atoms in the 9 and 9' positions and the hydrogen atoms in the 8 and 8' positions may be replaced by linkages connecting the said positions with each other and in which the anthraquinonyl radicles may be substituted.

4. A process for the manufacture of vat dyestuffs which comprises treating with a weak alkaline condensing agent having a reducing action an omega-omega'-tetrahalogeno-2,2'-dimethyl-1,1'-dianthraquinonyl.

5. A process for the manufacture of 2,2'-ethylene-1,1'-dianthraquinonyl which comprises treating with pyridine omega-omega'-tetrabromo-2,2'-dimethyl-1,1'-dianthraquinonyl.

6. As new article of manufacture 2,2'-ethylen-1,1'-dianthraquinonyl forming an orange powder dissolving in concentrated sulphuric acid to give an olive green coloration and dyeing cotton from a violet wine red vat yellow orange shades.

In testimony whereof we have hereunto set our hands.

MAX ALBERT KUNZ.
KARL KOEBERLE.

CERTIFICATE OF CORRECTION.

Patent No. 1,804,535.

Granted May 12, 1931, to

MAX ALBERT KUNZ ET AL.

It is hereby certified that error appears in the printed specification of the above numbered patent requiring correction as follows: Page 2, line 89, for the word "power" read powder; page 3, in the formula of claim 1, line 60, for "Ha" read Hal; and that the said Letters Patent should be read with these corrections therein that the same may conform to the record of the case in the Patent Office.

Signed and sealed this 4th day of August, A. D. 1931.
